W. L. SMITH

SPINDLE DEVICE

Filed July 7, 1924

Fig. 2.

UNITED STATES PATENT OFFICE.

WALTER LEE SMITH, OF GASTONIA, NORTH CAROLINA.

SPINDLE DEVICE.

Application filed July 7, 1924. Serial No. 724,639.

To all whom it may concern:

Be it known that I, WALTER L. SMITH, a citizen of the United States, residing at Gastonia, in the county of Gaston and State 5 of North Carolina, have invented a new and useful Spindle Device, of which the following is a specification.

This invention relates to a drive for spindles, one of the objects being to provide 10 a tension means whereby a band or belt utilized for driving a plurality of spindles can be kept under proper tension. Heretofore it has been necessary to utilize an individual band for each spindle, and as these 15 bands have become slack the yarn produced has been soft and the bobbins have not been sufficiently hard when wound. Bands heretofore used have also been objectionable because they are sometimes too tight and thus 20 absorb power unnecessarily.

It is an object of the present invention to provide a drive which will operate a plurality of spindles, will maintain a uniform tension at all times, and affect a uniform 25 twist of the yarn.

With the foregoing and other objects in view which will appear as the description proceeds, the invention resides in the combination and arrangement of parts and in 30 the details of construction hereinafter described and claimed, it being understood that changes in the precise embodiment of the invention herein disclosed may be made within the scope of what is claimed without departing from the spirit of the invention. 35

In the accompanying drawings the preferred form of the invention has been shown.

In said drawings— 40 Figure 1 is a plan view showing in slightly exaggerated form the drive mechanism combined with four spindles of the bobbin winder.

Fig. 2 is an enlarged section on line 2—2, 45 Fig. 1.

Fig. 3 is a section on line 3—3, Fig. 2.

Fig. 4 is a section on line 4—4, Fig. 2.

Referring to the figures by characters of 50 reference 1 designates the spindle bars of the machine between which is located the drive cylinder 2. Spindles have been indicated at 3 each of them being provided with a grooved collar or sheave 4 as ordinarily. The device constituting the present invention is adapted to be combined with four of

the spindles, two upon each of the rails 1. This mechanism includes a bracket 5, the upstanding portion of which is slotted transversely as at 6 so as to receive an attaching bolt 7. By providing this slot the bracket 60 can be adjusted laterally relative to the rail 1. Bolted or otherwise connected to the lower portion of the bracket is a hanger 8 having superposed parallel depressions 9 in which are adapted to be seated parallel 65 guide rods 10. These rods are clamped in the depressions by means of a plate 11 and journaled on the hanger 8 is a pulley 12. Slidably mounted on the upper rod 10 are spaced sleeves 13 formed on a carriage 70 75 14 and the lower portion of the carriage is forked as at 15 so as to straddle and slidably engage the lower rod 10. The carriage is formed with a stud 16 to which is connected a chain or other flexible device 17 mounted on the pulley 12. This flexible element carries a weight 18 as shown.

The carriage is provided with a yoke 19 which extends over the hanger 8 and also has one arm spaced from and lapping one side 80 of the carriage as shown particularly in Fig. 1. This arm is formed in its inner side with a recess 20 having an overhanging lip 21 and another recess 22 is formed in one side 85 of the carriage. In these recesses are seated bearing blocks 23 preferably of hard wood in which are journaled the ends of the shaft 24 of a large pulley 25. It will be noted that when these blocks are in their recesses one of them is overhung by one of the rods 90 10 so that when the parts are properly assembled, it becomes impossible for the blocks to become dislodged.

An endless belt is extended around the pulley 25 and thence to the sheaves 3 on a 95 pair of spindles on one of the rails 1, thence back to the sheaves 4 on a pair of spindles on the other rail 1 and finally around the cylinder 2 and back to a pulley 25. Thus it will be apparent that when the cylinder 2 100 rotates, motion will be transmitted therefrom through the belt to the four sheaves engaged thereby so that four spindles will be operated. The weight 18 pulls constantly on the carriage 14 and, consequently, the 105 pulley 25 will constantly pull on the rod or belt engaged thereby so as to hold the belt under proper tension and insure uniform winding of the bobbins.

It will be understood of course that the 110

bearing blocks can be removed readily simply by lifting them out of the recesses in which they are seated and substituting others.

What is claimed is:—

- 5 1. A device of the class described including an attaching bracket mounted for lateral adjustment, a hanger connected thereto, a clamping plate connected to the hanger, guide rods clamped at one end between the hanger and plate, a carriage mounted to slide between and along the guide rods, an arm at one side of and carried by the carriage, there being recesses within the inner side of the arm and one side of the carriage, bearing blocks removably seated within the recesses, a shaft journaled within the blocks, a belt engaging pulley rotatable with the shaft and between the carriage and its arm, a pulley upon the hanger, a weight, 10 and a flexible connection between the weight

and carriage, said connection being mounted on the pulley of the hanger for holding the carriage normally drawn toward the hanger.

2. In a device of the class described a bracket for attachment to a spindle bar, a hanger depending from the bracket, a pulley thereon, parallel guide rods, means for clamping the rods at one end against the hanger, a carriage between and slideable along the rods, a weight, a flexible connection between the weight and carriage and mounted on the pulley for holding the carriage normally drawn toward the hanger, an arm upon one side of the carriage, and a belt engaging pulley detachably journaled between the arms and the carriage. 25 30 35

In testimony that I claim the foregoing as my own, I have hereto affixed my signature.

WALTER LEE SMITH.
